UNITED STATES PATENT OFFICE.

JOHN F. AMES, OF PORTLAND, OREGON.

PRINTING-PRESS.

SPECIFICATION forming part of Letters Patent No. 686,380, dated November 12, 1901.

Application filed February 7, 1901. Serial No. 46,367. (No model.)

To all whom it may concern:

Be it known that I, JOHN F. AMES, a citizen of the United States, residing at Portland, county of Multnomah, State of Oregon, have invented an Improvement in Printing-Presses; and I hereby declare the following to be a full, clear, and exact description of the same.

My invention relates to improvements in printing-presses.

10 It consists in a novel construction of the cylinder and means for securing the type or characters thereon from which the impression is to be made, means in unison therewith by which the type or printing surface is protected from undue pressure from the surface on which the printing takes place, means by which the ink is prevented from being transferred to the protecting strips, means whereby all the devices are securely locked 20 to the cylinder by a single operation, and details of construction to be more fully described hereinafter.

Referring to the accompanying drawings, Figure 1 is a longitudinal section on the line *w w*, Fig. 2. Fig. 2 is a plan, the ink-well and distributing-rollers being omitted. Fig. 3 is a view of the type-cylinder, the type-form being omitted. Fig. 4 is a longitudinal section on the line *x x*, Fig. 5. Fig. 5 is a 30 transverse section on the line *y y*, Fig. 4. Fig. 6 is an end view of a clamp. Fig. 7 is a side elevation of a bearing-strip. Fig. 8 is a transverse section on the line *z z*, Fig. 7.

My invention is especially designed for the 35 purpose of securing printing types or characters upon a revolving cylinder, so that they may be employed for printing bags, the wooden sides or parts of which boxes are constructed and for like purposes.

40 The press consists of a bed *A*, upon which the material to be printed is supported; a cylinder *2*, adapted to carry the type, engraved surface, or form from which the impression is to be made; an ink-well *3*, and distributing-rollers *4*, so disposed that ink from the well is transferred as desired to the form or printing surface during the revolution of the cylinder. Any suitable or well-known mechanism or gearing may be employed to 45 drive the various parts in unison, consisting of driving-pulleys and gears, which may be

arranged as shown in the drawings. The cylinder is made with longitudinal slots or channels, as at *5*, and in line with these channels the locking-clamps *6* are movable. These 55 clamps have shanks extending through the slots *5*, and within and interior to the cylinder are formed the nuts *7*, which are adapted to travel upon the screws *8*. These screws are of any suitable number and extend longitudinally from end to end of the cylinder, 60 having shoulders which abut against the inner ends of the cylinders, and thus retain the screws in position. The ends of the screw-shanks extend through one end of the cylinder and are made of convenient form, as 65 shown at *9*, to receive a wrench or means by which they may be rotated. The screws are made with right and left threads, respectively, upon opposite sides of the central line, 70 and when the screws are turned in one direction the locking clamps or lugs *6* are caused to approach and clamp the edges of the printing block or form or intervening strips, so as to firmly lock the form upon the cylinder. 75 By reversing the turn of the screws the clamps are retracted, thus allowing the form to be removed.

When this press is employed for printing the boards from which boxes are made, a 80 difficulty arises from careless sawing of the boards, which may vary as much as a quarter of an inch, more or less, in thickness, and which, therefore, will bring very uneven pressure and strain upon the printing-surface. 85 These boards are piled in considerable numbers between upright guides or holders *10* upon the bed *A*, and by means of a chain *11*, having lugs projecting from it at intervals, the lowermost of the boards in the pile is advanced so as to pass between the printing-cylinder and a corresponding pressure-roller below, by which sufficient pressure is brought to bear to imprint the words or characters upon the wood. When the apparatus is set to 90 properly print the thinnest of these boards, it will be manifest that when thicker boards pass between the rollers a serious strain and pressure is brought to bear upon the type-surface. These surfaces when used for printing boxes are usually made of very hard metal, which is often broken by unequal 100

strains, and in order to protect the type-surface from the strains caused by the difference in thickness of the boards I have shown bearing-strips 12, curved to the same form as the type-surface, fitting the cylinder and having tongues, as at 13, which extend into the slots 5 of the cylinder. These guard-strips 12 are interposed between the clamping-lugs 6 and the edges of the form, and the meeting edges 10 of the two and also the contiguous edges of the locking-clamps are beveled, as shown at 14, or otherwise made so that when they are pressed together the protecting-strips act to hold the printing-form in place, and the 15 clamps in turn lock the protecting-strips. These strips are made of a sufficiently less height than the type or printing surface, so that a good impression of the latter will be made upon any material upon which the printing 20 is to take place; but when by reason of greater thickness of the material an undue pressure is brought upon the printing-surface this pressure is received upon the parallel protecting-strips 12, and the printing 25 surface is thus relieved of all pressure except sufficient to secure a good impression. These strips afford protection when thick boards are passed through the press, because the lower cylinder 30 has underneath it a heavy piece 30 of rubber 31 at each end of the shaft, so that when any extra pressure is occasioned by the passing of a board of unusual thickness between the rollers the rubber yields and permits the thick board to pass through. If the 35 lower cylinder was not supported by these rubbers, but the shaft fixed to move rigidly in the boxes, whenever a thick board was passed between the cylinders the brand and even the protecting-strips would be forced into 40 the board to the extent of the extra thickness and the press would stop or something would break. The type or printing surface being composed of letters or a design more readily press into the brand than would the protecting-strips on the side, which presents the planed solid surface. The chief strain on the type or printing surface is when it first comes in contact with the board to be printed. If, for instance, the press is set to print a board 45 one-half inch thick and one three-fourths inch thick is presented by the feeding-lug to be printed the brand as it revolves on the upper cylinder would strike the board with a severe blow. The protecting-strips by passing entirely around the cylinder, or at least 50 half-way, receive the board as soon as it is pushed in by the feeding-lug on the chain above the lower cylinder, so that when the brand is presented to the board the lower cylinder 55 has been depressed by the protecting-strip sufficiently to relieve the type or printing surface of all strain. In order to prevent the ink on the distributing-rollers from being deposited upon these strips and eventually 60 making unseemly marks upon the material which is to be printed, I have shown protecting strips or guards which consist of thin,

preferably elastic, plates of metal 15, so curved as to partially follow the contour of the inking-roller and to lie between this roller and the strips 12, which are clamped upon each side of the printing-surface. The convexed lower surfaces of the guards 15 rest upon the curved protecting-strips 12, and any ink which may have been distributed upon the inking-roller upon the width of the surface to be printed will be thus prevented from being deposited upon the protecting-strips 12. These guards 15 may be supported in any suitable or convenient manner from 75 parts of the printing-press. As here shown, they are fixed to metal blocks 16, which are grooved or channeled to fit a bar 17, which extends conveniently across the frame of the apparatus and by means of hooks, as at 18, 80 they are supported upon a rod or shaft 19, extending across from one side to the other of the frame. This allows them to be readily removed whenever desired, and they may be locked in position by set-screws, as at 20. 85

Having thus described my invention, what I claim as new, and desire to secure by Letters Patent, is—

1. The combination in a printing-press of a cylinder adapted to carry the printing-surfaces, slots or channels made longitudinally in the cylinder, clamps guided and movable in said slots and having threaded interior nuts, segmental guard-strips interposed between the adjacent edges of the clamps and 95 form or printing surface and of less height than said surface, whereby undue pressure upon said surface is relieved, and screws passing through said nuts and turnable so as to advance the clamps and cause the strips to 100 grip the printing block or form, or release it. 105

2. The combination in a printing-press of a cylinder, a form or printing surface fitted thereto, said cylinder having longitudinal slots or channels made in its surface, segmental strips of less height than the form or printing surface and having edges to grip the edges thereof, clamps adapted to grip the opposite edges of the strips and having shanks passing through the slots and interior nuts, 110 right and left threaded screws passing respectively through the nuts of the clamps upon opposite sides of the printing-plate, said screws having shoulders abutting against the inner ends of the cylinder and projecting 115 through one of the ends having means to through a wrench or device may be applied whereby they may be turned to cause the gripping-clamps to approach or recede in unison. 120

3. The combination in a printing-press of a cylinder, a type form or plate fitting thereon, clamps and screws by which they are advanced toward or retracted from the plate, curved blocks interposed between the clamps and the plate upon each side and adapted to 125 be interlocked therewith when the clamps are forced against them, inking-rollers adapted to supply ink to the printing-surface, and means for keeping the ink from the blocks 130

upon each side of the printing-plate, consisting of guards interposed between the inking-roller and the blocks.

4. The combination in a printing-press of a cylinder having longitudinal slots in its surface, a printing form or plate fitting the surface of said cylinder, screw-actuated clamps movable in the slots to lock or release the printing-plate, curved strips interposed between the lugs and the plate having the surfaces of such height as to relieve pressure upon the plate, a roller by which ink is applied to the printing-surface, guards interposed between the roller and the curved strips at each side of the printing-plate and blocks to which the guards are secured, said blocks having means for securing them to the supporting parts of the press.

5. The combination in a printing-press of a longitudinally-slotted cylinder, a printing-form curved to fit thereon, clamps slideable in the slots, guard-strips interposed between the

edges of the clamps and printing-form, and reversely-threaded screws engaging and actuating the clamps upon opposite sides of the form, said strips having edges adapted to interlock with the edges of the form and clamps. 25

6. The combination in a printing-press of a longitudinally-slotted cylinder, a curved form or printing-plate upon the cylinder, segmental guards upon each side of the form and having locking edges, said guards having lugs on their inner faces adapted to engage the slots in the cylinder, means engaging the outer edges of the guards, an impression-roller, and yielding journal-boxes therefor whereby the pressure upon the form is regulated. 30 35

In witness whereof I have hereunto set my hand.
